UNITED STATES PATENT OFFICE.

LEWIS H. LEE, OF TORONTO, ONTARIO, CANADA.

HARVESTING-MACHINE.

SPECIFICATION forming part of Letters Patent No. 252,681, dated January 24, 1882.

Application filed April 23, 1881. (No model.)

To all whom it may concern:

Be it known that I, LEWIS HART LEE, of the city of Toronto, in the county of York, in the Province of Ontario, Canada, manufacturer, have invented certain new and useful Improvements in Harvesting-Machines, of which the following is a specification.

The invention relates more particularly to that class of harvesting-machines in which the knife is driven by a vibrating arm from a differential oscillating gear-wheel mounted on the frame of the machine and operated by a toothed wheel on the master-wheel of the machine.

The invention consists in the combination, with the said vibrating arm and connections, of an oblique brace arranged underneath said arm, with one end connected to the outer end of said arm by a ball-and-socket joint and the other end connected by a similar joint to the main frame at a point below the main axle, for the purpose of bracing and supporting the vibrating arm while permitting it to vibrate.

In the drawings, Figure 1 is a plan of the machine. Fig. 2 is a side elevation, showing the brace. Fig. 3 is a detail of the frame.

A is the traction-wheel of the machine; B B', the differential driving-gear.

C is the vibrating arm, which actuates the cutter; and D the frame of the machine, provided with the arm D', which connects with the inside shoe of the cutting apparatus.

E is the ball-joint, upon which the gear-wheel B' is supported.

F is my brace, flexibly connected by means of a ball-and-socket joint at one end to the vibrating arm C, and extending from this point in an oblique direction, its other end connected by a similar joint to the pin G, or its equivalent, on the main frame of the machine at a point beyond the center of the ball-joint of the differential gear, as indicated. It will be seen that an oblique brace connected in this manner to the parts specified will support and brace the vibrating arm without interfering with its vibrating movement.

What I claim as my invention is—

In a harvesting-machine, the combination, with the differential gearing B B' and vibrating arm C for operating the cutter-bar, of the oblique brace F, arranged underneath said arm, one end of said brace being connected by a ball-and-socket joint to the outer end of said arm and the other end connected by a similar joint to the main frame of the machine at a point below the main axle, whereby the vibrating arm is braced and supported while it is permitted to vibrate, substantially as described.

LEWIS HART LEE.
